BUBBLE TRAY

Hans C. Glitsch, Dallas, Tex.

Application August 4, 1940, Serial No. 351,295

4 Claims. (Cl. 261—114)

This invention relates to new and useful improvements in bubble trays.

One object of the invention is to provide an improved bubble tray which is so arranged that the parts thereof; namely, the floor, risers and bubble caps, may be constructed of a corrosion-resistant material, such as stainless steel without increasing the cost beyond prohibitive limits.

An important object of the invention is to provide an improved bubble tray wherein the floor is constructed of a plurality of sections, each section having means coacting with the risers and bubble caps, whereby the entire assembly may be readily assembled in a minimum time and with a minimum amount of labor.

A particular object of the invention is to provide an improved bubble tray composed of a plurality of sections, each section being constructed of a relatively thin material and having the required riser openings therein; the material immediately surrounding the opening being extruded or offset to form an annular flange, either at a right angle or at an incline with relation to the surface of the section, whereby rigidity is added to the section to compensate for the loss of rigidity due to the formation of the openings or due to the relative thinness of the section.

Another object of the invention is to provide an improved bubble tray having riser openings therein, together with an integral annular flange surrounding each opening; said flange being adapted to coact with a tubular riser so as to properly center and locate the riser and also to maintain a fluid-tight seal between the riser and tray.

A particular object of the invention is to provide an improved bubble tray wherein the risers having the bubble caps associated therewith are mounted on the tray so as to be incapable of lateral movement, whereby a single holdown or retaining member may be employed for holding each row of bubble caps in position on their respective risers.

A further object of the invention is to provide an improved bubble tray, of the character described, wherein the flange surrounding each opening may be varied so as to coact with different types of riser and bubble cap units, whereby any desired units may be employed.

Still another object of the invention is to provide an improved holdown element for bubble caps which is so constructed that maximum rigidity in both horizontal and vertical axes is obtained with minimum fabrication and weight; said bar being shaped so as to permit easy access

5 to the tie-down bolts extending therethrough, while disposing said bolts out of the way of workmen, the bar also presenting a relatively broad flat surface for engaging the bubble caps and having a low center of gravity when in its proper position to insure stability in use.

A construction designed to carry out the invention will be hereinafter described, together with other features of the invention.

10 The invention will be more readily understood from a reading of the following specification and by reference to the accompanying drawings, in which an example of the invention is shown, and wherein:

15 Figure 1 is a partial, transverse, vertical, sectional view of a bubble tower, illustrating a bubble tray, constructed in accordance with the invention, mounted therein.

Figure 2 is a partial plan view of the tray, Figure 3 is an enlarged transverse, vertical, sectional view of one section of the tray floor,

Figure 4 is a plan view of the parts shown in Figure 3,

Figure 5 is a bottom view of the bubble cap illustrated in Figures 1 to 4, and

Figures 6 and 7 are enlarged views, illustrating modifications of the flanges in the tray sections and also showing different risers mounted thereon.

20 In the drawings, the numeral 10 designates a portion of a bubble tower which has a plurality of trays T mounted therein in the usual manner. It is preferable that the tower be constructed in accordance with my aforesaid co-pending application, which matured into Patent No. 2,210,808, August 6, 1940, but it is particularly noted that the present invention is not to be limited to use with the particular tower shown and described in said patent, as it may be successfully used in any bubble tower.

25 The present invention resides in the bubble tray assembly T and includes a plurality of floor sections 11 which are supported upon transverse trusses 12 extending in parallel relation across the interior of the tank. Each floor section is formed of a relatively thin material so as to be light in weight, stainless steel being preferable not only because of its light weight but also because it is resistant to corrosion. As is clearly shown in Figure 2, each section is narrow in width, as compared to its length and each section spans the space between adjacent trusses 12. The longitudinal edge portions of the sections rest upon the trusses (Figure 3) and the edge 30 of each section is spaced from the adjacent

trusses, the adjacent edges being frictionally clamped, in such spaced relation, to the trusses by bolts 13, suitable washers 14 being interposed between the bolt heads and sections. The frictional clamping and the spacing sections provide a mounting for the sections which permits the same to undergo lateral movement due to thermal expansion and contraction.

Each tray section is formed with a plurality of riser openings 15 which are arranged in longitudinal rows, as is clearly shown in Figure 2. As is well known, the riser openings are provided in the tray floor to permit gas to rise upwardly in the tower. Since the tray floor sections are constructed of a relatively thin material and also since each section is relatively long, said sections do not have a great deal of inherent rigidity and, when the riser openings 15 are formed therein, a decrease in the rigidity of the sections results. In order to compensate for the loss of rigidity due to the provision of the riser openings and also to strengthen each section, the material around each riser opening is extruded to form an integral annular flange 16 around the opening. As illustrated in Figure 3, the flange is at substantially a right angle to the plane of the floor section and extends upwardly therefrom. Since a flange 16 surrounds each opening and a plurality of openings are provided in each section, it follows that a number of said flanges are present in each section, whereby the rigidity and strength of the section is increased.

The flanges 16 not only add rigidity to the floor sections 11 but also provide a means which is adapted to coact with the usual bubble cap risers 17 which are associated with each riser opening 15. Each riser 17 is tubular and has its lower end engaged over the flange 16 with its lower edge resting upon the top of the section and, manifestly, the flange prevents lateral displacement of the riser. It is preferable that the internal diameter of the riser be substantially equal to the external diameter of the flange, whereby the riser fits snugly on the flange so as to provide a fluid seal around the flange. Although each riser may be constructed of any suitable material, it is desirable that said material be relatively thin and corrosion-resistant, stainless steel having been found satisfactory.

Each riser 17 has its open upper end terminating at some distance above the tray floor and a bubble cap 18 is arranged to be mounted on said riser. The bubble cap is preferably constructed of a relatively thin, non-corrosive material and has a diameter which is considerably larger than the external diameter of the riser 17, whereby the cap will enclose said riser. The cap is formed in the usual way, being provided with the depending annular skirt 19 and the lower end of this skirt is spaced from the tray floor. The skirt is formed with suitable vents or openings 20 which are formed in the lower portion thereof. The cap is supported on the riser 17 by means of a spider 21, said spider being secured to the underside of the top of the cap by welding, or other suitable means. As is clearly shown in Figure 5, the spider includes a trio of radial arms 22, each of which have their outer ends cut out or recessed to provide a shoulder 23. The length of each arm is such that that portion below the shoulder 23 is insertable within the bore of the riser 17, whereby the shoulder 23 rests upon the upper edge of the risers 17. Manifestly, the spider not only serves to support the bubble cap 18 in position on the riser, but also

prevents a lateral displacement of said cap with relation to the riser.

As has been explained, the riser openings 15 are disposed in longitudinal rows within each section 11 of the tray floor and, therefore, the bubble caps 18, when in position, are also disposed in longitudinal rows (Figure 2). For fastening the bubble caps 18 to prevent upward displacement thereof, an elongate holdown or retaining bar 24 is provided for each row of bubble caps. This holdown bar is constructed of a relatively thin material and is formed with a relatively wide base flange 25. At its upper end, the material of which the bar is formed is turned inwardly so as to form a small flange 26 which overlies the base flange 25. The holdown element or bar 24 is placed upon the bubble caps 18 in a particular row and the base flange 25 rests upon or engages the top of said bubble caps. Since the base flange 25 is relatively wide, an amplified contact surface is provided between the holdown bar and the bubble caps.

For fastening the holdown bars 24 in a position retaining the bubble caps 18 on their respective risers, the base flange 25 of said bar is provided with a plurality of openings 21. Each opening is located in the space between the bubble caps 18 and an elongate fastening bolt 28 which extends upwardly through the tray floor or section 11 also passes through the opening 27. A fastening nut 29 is threaded onto the upper projecting end of the bolt 28 and, when tightened on said bolt, serves to pull the holdown bar downwardly into tight engagement or contact with the bubble caps 18. Obviously, since the nut 29 is disposed immediately above the base flange 25, said nut is readily accessible, whereby manipulation thereof to fasten or release the bars 24 may be readily accomplished. Also, since the bar 24 extends upwardly above the nut, said nut is completely out of the way. It is pointed out that the small flange 26 at the upper end of the bar 24 increases the rigidity of the bar, whereby the bar may be made of a relatively thin, light material. Also, the provision of the lateral flange 26 eliminates sharp edges which might be dangerous to a workman performing some operation on the tray.

From the above, it will be seen that a simple bubble tray assembly is provided. The tray floor is constructed of a plurality of sections, each of which is made of a relatively light, thin material. Each section is provided with the riser openings 15 which permit the vapors to rise upwardly past the tray floor. Each opening is surrounded by the offset or flange 16 which not only adds rigidity to the section but also coacts to center the riser 17 and to prevent lateral displacement thereof on the tray floor. The bubble cap 18 is mounted on each riser 17, being merely placed thereon and being supported and held against lateral displacement by the spider 21 which is secured to the underside of the top of said cap. The bubble caps 18 of each row are held against upward displacement on their respective risers 17 by the improved retaining element 24 which is tied down to the floor 11 by means of the bolts 28 and nut 29. With this arrangement, a single holdown or retaining element may be provided for a plurality of the bubble caps and it is not necessary that each cap have a separate holdown means. As pointed out, the angular construction of the holdown bar provides for maximum rigidity of the bar in both a horizontal and vertical axis. By making the bubble tray

in this manner, the construction of the various parts thereof of stainless steel or other similar material is facilitated and, therefore, the entire tray may be made corrosion-resistant.

As was pointed out above, the tubular riser preferably has an internal diameter substantially equal to the external diameter of the flange 16 so as to have a snug engagement therewith, whereby a fluid seal is provided. However, it might be found necessary to employ a sealing gasket to seal the joint between the lower end of the riser and the flange. In such case, the riser is constructed as shown in Figure 6, being provided with an offset or enlargement 17a at its lower end. This offset snugly engages over the flange 16 and a suitable packing gasket 30 may be interposed between the lower edge of the riser and the tray floor to assure a positive sealing of the joint.

It is not essential to the invention that the flange 16 be disposed at a right angle to the tray floor and, in Figure 7, an inclined flange 18a is illustrated. This flange inclines inwardly of the riser opening 15. A riser 17 has its lower end flared or inclined outwardly as shown at 17a and this flared portion has an inclination which is complementary to the inclination of the flange 18a, whereby the riser 17 may be placed on said flange. The flange 18a is sufficient to prevent lateral displacement of the lower end of the riser 17 and, therefore, it is possible to employ the bubble caps 18 and hold-down element 24, as shown in Figure 3.

The foregoing description of the invention is explanatory thereof and various changes in the size, shape and materials, as well as in the details of the illustrated construction, may be made, within the scope of the appended claims, without departing from the spirit of the invention.

What I claim and desire to secure by Letters Patent is:

1. A bubble tray assembly including, a tray floor including a plurality of sections, each section being elongate and having a plurality of spaced openings each surrounded by a flange, riser collars having their lower ends in fluid tight connection with the flanges of the openings of said sections, bubble caps overhanging the upper ends of said collars and supported thereon, each cap having a spider secured to the underside of its top, each spider including arms which extend

from a common center and which engage the rim of the collar beneath the bubble cap, whereby said arms brace each other and support the cap in position on its collar, a unitary hold-down element overlying said caps and immovably holding them on said collars, and means for fastening said hold-down element in place.

2. A bubble tray assembly including, a plurality of sections, each section having a plurality of spaced openings provided with riser collars open at their upper ends, bubble caps overhanging the collars and having spiders secured to the undersides of their tops, each spider including arms which extend from a common center and which engage in and rest upon the upper rims of the collars, said arms functioning to brace each other and also to position the cap on the collar, a hold-down member extending across the caps and resting upon their tops, and means for rigidly fastening said member in engagement with said caps, whereby the spiders are rigidly held on the rims of said collars.

3. A bubble tray assembly including, a plurality of sections, each section having a plurality of spaced openings provided with riser collars open at their upper ends, bubble caps overhanging the collars each cap having a spider secured to the underside of its top which spider comprises a trio of vertically disposed radially extending bars having their inner ends permanently secured to each other whereby each bar braces the others to prevent lateral bending of said bars, the spiders of said bubble caps engaging in and resting upon the upper rims of the collars, and hold-down means associated with the caps for rigidly fastening said caps in position overhanging the collars and for rigidly holding the spiders on the rims of said collars.

4. As a sub-combination in a bubble tray assembly, a bubble cap having a closed top, a spider secured to the underside of said top, said spider comprising a trio of vertically disposed bars which extend from the center of the top of said cap to a point terminating short of the periphery of the cap, the inner ends of said bars abutting each other at the center of the top, and means for permanently fastening the abutting inner ends of the bars to each other, whereby each bar braces and reinforces the other bars to prevent lateral displacement and bending of said bars.

HANS C. GLITSCH.
